UNITED STATES PATENT OFFICE.

FREDERICK D. JONES, OF ALHAMBRA, CALIFORNIA.

DISPLAY-CARD-RACK SECTION.

Application filed November 26, 1921. Serial No. 517,934.

To all whom it may concern:

Be it known that I, FREDERICK D. JONES, a citizen of the United States, residing at Alhambra, in the county of Los Angeles and 5 State of California, have invented a new and useful Display-Card-Rack Section, of which the following is a specification.

This invention relates to the novel construction for a card rack section as embodied 10 in my former application filed June 8, 1920, Serial No. 387,792.

An object of this invention is to provide cheap, simple, and compact means which may be easily applied to a suitable support 15 with slight expense of time and labor, to provide a rack for holding perception cards in schools.

The invention may be applied to other uses of a like character.

20 An object of this invention is to provide a rack, for holding various lengths of perception cards, that will afford maximum ease of inserting and withdrawing said cards.

Other objects, advantages and features of 25 invention may appear from the accompanying drawing, the subjoined detail description and the appended claim.

The accompanying drawing illustrates the invention.

30 Figure 1 is a front view of a rack constructed of a wooden frame and a plurality of my newly invented slats applied thereto.

Fig. 2 is a sectional elevation on line x^2 , Fig. 1, of the rack shown in Fig. 1.

35 Fig. 3 is a fragmental front elevation of one end of a slat attached to its support, a fragment of which is shown.

Fig. 4 is an end view of said slat detached.

Fig. 5 is a fragmental plan of the slat 40 shown in Fig. 3.

Fig. 6 is a back view of the slat fragment shown in Figs. 3, 4 and 5.

Fig. 7 is an enlarged fragmental perspective front view of one end of one of the slats.

45 Fig. 8 is a like perspective view of the back of said slat detached.

The novel card rack section comprises a slat made of a single piece of sheet metal comprising a broad elongate body 1, a lap 50 2 at the top, a bend 3 at the bottom, a retaining limb 4 extending from end to end of the slat and terminating in an outwardly bent lip 5.

The upturned portion 4 is practically

parallel with the body portion 1 of the slat 55 and the out-turned lip 5 simply serves as a guide to allow the cards to be inserted without difficulty.

In practice the slats are made from strips of thin sheet metal, the upper lap 2 being 60 folded flat against the body and on the reverse side from the lower bend 3 which is of sufficient width to loosely accommodate the thickness of cards intended to be inserted. Such cards being freely movable horizontally 65 in the groove comprising said bend 3, upturned portion 4 and body 1. The lap 2 extends a sufficient distance down the body to give a required rigidity to the upper part of the slat, the lower bend gives additional 70 strength and rigidity. The slats are provided at intervals with holes 6 through which tacks 7 may be driven to fasten the slats to the uprights 9.

The slats are preferably formed with a 75 rounded top bend as at 8 between the supporting portions or points of attachment 10 and such supporting portions 10 are preferably flattened as indicated in Figs. 3, 5, 6, 7 and 8. This adds to the stiffness of the slat 80 and the completed rack is thus made more rigid.

In practice the slats are easily bent up from the strips of thin sheet metal having the width required for the lap 2, body 1, 85 bend 3, upturned portion 4 and lip 5. And these parts are formed in the manner common in the sheet metal worker's art. Then the slats are ready for market and may be set up for use by simply nailing, tying or 90 tacking them to some suitable support, as a wall, not shown, or to a frame such as that formed by the uprights 9, base 11 and rail 12.

In practice the body 1 is considerably 95 wider than the upturned portion 4 so as to engage the edge of the cards, intended to be inserted into the groove formed by the upturned portion 4 and act as a guide to such cards, which at times are 18 inches to 24 inches in length, or said body may deflect 100 the cards against the outwardly projecting upper lip 5 and thereby facilitate the introduction of the cards into the groove.

I claim:

A card rack section comprising a broad 105 elongate body forming the back of said section, and having a lap along its upper longitudinal margin, and bent at its lower edge

to form an upturned portion having a groove adapted to loosely hold and permit free horizontal movement of cards therein and there along; and said upturned portion terminating in an outwardly projecting upper lip; said body being adapted to guide cards into said groove and to deflect cards therefrom and against said outwardly projecting upper

lip, thereby facilitating the introduction of cards into said groove.

In testimony whereof, I have hereunto set hand at Los Angeles, California, this 18th day of November, 1921.

FREDERICK D. JONES.
